UNITED STATES PATENT OFFICE.

ALBERT C. MURPHY, OF NEW YORK, N. Y., ASSIGNOR TO P. H. MURPHY COMPANY, OF PARNASSUS, PENNSYLVANIA, A CORPORATION OF PENNSYLVANIA.

METAL CAR-ROOF.

1,191,213.

Specification of Letters Patent. Patented July 18, 1916.

Application filed October 6, 1915. Serial No. 54,301.

To all whom it may concern:

Be it known that I, ALBERT C. MURPHY, a citizen of the United States, and a resident of the city of New York, in the county of New York and State of New York, have invented a new and useful Improvement in Metal Car-Roofs, of which the following is a specification.

This invention relates to flexible metal roofs for freight cars wherein the metal roof sheets are arranged crosswise on top of the car and are loosely secured at the ridge and eaves to the roof substructure, and adjacent roof sheets are connected by non-rigid standing seams or joints.

The objects of the invention are to prevent wearing through or tearing of the roof sheets in service, to protect the sheets where the wear and tear is greatest, to do away with holes through the roof sheets for the securing means, and to provide for the convenient removal and replacement of worn and damaged roof sheets; and to maintain the joints between the roof sheets tight under service conditions.

The invention consists in the combination of a roof section comprising either one or two roof sheets, which section extends from eaves to eaves and is arranged astride the ridge at its middle where it is provided with a central boss, with a ridge seam cover provided with a mating boss at its middle adapted to cooperate with the boss in the roof section to retain the roof section in place and to permit of sufficient movement of the roof sheets to prevent their becoming torn or cracked in service.

Further objects of the invention appear in connection with the following description of the car roof constructions shown in the accompanying drawings; and what the invention consists in is more particularly defined in the appended claims.

In the drawings, wherein the same reference characters designate the same or similar parts in the several views, Figure 1 is a plan view of a portion of a car roof embodying the invention, the running boards and seam covers being partly broken away to show the roof sheets; Fig. 2 is a cross-section of the same at the eaves, on the line 2—2 in Fig. 1, drawn to a larger scale; Fig. 3 is a cross-section on the line 3—3 in Fig. 1, drawn to the same scale as Fig. 2.

Figs. 4 and 5 are enlarged cross-sections

of the ridge construction, on the lines 4—4 and 5—5 in Fig. 1, respectively; Figs. 6 and 7 are cross-sectional views similar to Figs. 4 and 5, showing a modified form of the invention.

In the drawings, the invention is shown applied to a car having a wooden roof substructure consisting of roof boards 11 supported at their ends on a side plate 12 and ridge piece 13, but the substructure may be constructed in any manner desired of either wood or metal. The roof sheets 14 are arranged side by side in parallel rows on opposite sides of the ridge, and are spaced apart sufficiently to permit wooden battens 15 to be laid between the roof sheets of each row. The ends of the roof sheets on opposite sides of the ridge are arranged in alinement crosswise of the car, and the battens on each side of the car are in alinement and meet at the ridge.

The side edges of each roof sheet are provided with upstanding flanges 16 with in-turned extremities 17 which slope down toward the body portion of the sheet. The side flanges of adjacent roof sheets are covered by side seam covers 18 which are supported on the battens 15. These side seam covers have side walls 19 which are turned in at their bottoms, and the in-turned edges 20 of which are hooked under the extremities 17 of the side flanges of adjacent roof sheets, as shown in Fig. 3. This construction provides a loose but watertight connection or joint between the sides of adjacent roof sheets. The invention is not restricted to this side seam construction, and any sufficiently flexible seam or joint for connecting the roof sheets along their sides may be used.

The eaves ends of the roof sheets are turned under, forming hooks or rebends 21 on their under sides which are hooked into the folded-over inner edges 22 of flashing strips 23, as shown in Fig. 2. The flashing strips are nailed or otherwise secured along the eaves of the car between the battens. Angle-shaped eaves clips 24 are secured to the side of the car below the ends of the roof sheets, with their top legs projecting inwardly over the eaves ends of the roof sheets 14 and side seam covers 18 to hold them down. The eaves clips are detachably secured to the fascia board 25 by bolts, and may be quickly removed and replaced when

desired. They rest loosely upon the roof sheets without clamping them, so the roof sheets are free to move both lengthwise and crosswise of the car at the eaves. The invention is not restricted to this means of securing the roof sheets at the eaves, and any suitable method for loosely holding the eaves ends of the roof sheets may be used.

At the ridge, the roof sheets are secured 10 by ridge seam covers 26, which are arranged over the sheets longitudinally of the car, the ends of the ridge covers terminating close to the side flanges of the roof sheets. These ridge covers are inverted channel shape, 15 with vertical side walls 27 and wide flat tops. The lower edges of the side walls 27 have outturned flanges 28, which stiffen the side walls and aid in stiffening the ridge covers against both vertical and sidewise bending.

The ridge ends of the side seam covers 18 and the ends of the ridge seam covers 26 are secured in position by square corner caps 30, the side walls 31 of which are recessed to 25 fit over the seam covers. These corner caps are bolted to the ridge pole by bolts 32 which also secure the running board saddles 33 in position. The running boards 34 may be secured to the saddles in any suitable manner. The running board saddles rest on the 30 side seam covers 18 and battens 15, and hence the weight of the running board saddles and running boards is not carried on the roof sheets, which are freely movable 35 under the side and ridge seam covers within the limits of the side walls thereof.

In the form of construction shown in Figs. 1 to 5, inclusive, the roof sheets 14 extend from eaves to ridge, and have upstanding ridge flanges 35 near their ridge ends. 40 The upper extremities of the flanges 35 are bent outward, forming horizontal raised margins 36 which overlap across the ridge. At the middle point of each marginal portion 45 36 is an upstanding pivot boss 37, the bosses on overlapping sheets fitting into each other. The middle points of the top walls of the ridge covers 26 are provided with upstanding pivot bosses 29 which receive the 50 ridge flanges of the underlying oppositely disposed roof sheets and thereby form a pivotal support or fulcrum in which the roof sheet bosses may turn.

The ridge flanges 35 of the roof sheets are 55 slanted or inclined inwardly and upwardly from the ridge ends of the body portions of the respective roof sheets. The side walls 27 of the ridge seam covers 26 are spaced from the flanges 35, and have straight outturned 60 flanges 28 adapted to rest upon the roof sheets near the flanges 35 to form a watertight joint with the roof sheets while permitting them to move around the pivot bosses to accommodate themselves to the 65 distortions of the substructure in service. The

slant or inclination of the flanges 35 forms spaces between them and the seam covers which catch water flowing under the edges 28 and prevent it from creeping over the flanges 35 and into the car.

In the modified form of the invention shown in Figs. 6 and 7, the top face of the ridge pole 38 is convex, and the ridge ends of the roof boards 39 are let into grooves along the top edges of the ridge pole in 75 order to avoid a sharp ridge corner. The roof sheets 40 extend from eaves to eaves, and the middle or ridge portion of each of the roof sheets is slightly convex, the middle points of the curved middle portions being 80 bossed up to form pivot bearings 41 midway between the battens.

The curved ridge portions of the roof sheets are covered by ridge seam covers 42 which are likewise curved to conform to the 85 curved ridge of the roof sheets, and which rest on the roof sheets. Midway of their length the ridge seam covers 42 are provided with upwardly projecting bosses 43 conforming to the bosses 41 of the roof sheets. The 90 two ends of each ridge seam cover stop short of the inturned extremities 17 of the flanges 16 of the underlying roof sheets, and are secured in longitudinal alinement by the inverted channel shape ridge caps 44, and 95 thereby the roof sheets are retained in position on the roof substructure against sliding crosswise. The roof sheets are free to pivot or swing on the bosses 41 and 43, and can thereby accommodate themselves to the 100 distortions of the substructure which occur in service.

It is evident that other modifications of the ridge construction can be made without departing from the invention, and this invention is not restricted to any one of the arrangements shown and described.

I claim the following as my invention:

1. A car having a roof substructure in combination with metal roof sheets laid on said substructure crosswise of the car, metal ridge covers resting on said roof sheets in longitudinal alinement with the center line of said car and secured at their ends to said substructure, said ridge covers having pivot 110 bosses at their middles and said roof sheets having pivot bosses registering with the pivot bosses of said ridge covers, and means for loosely securing the eaves ends of said roof sheets, whereby said roof sheets are 120 retained on said substructure.

2. A car having a roof substructure in combination with metal roof sheets laid on said substructure crosswise of the car, metal ridge covers resting on said roof sheets in 125 longitudinal alinement with the center line of said car, ridge caps overlying the ends of said ridge covers and secured to said substructure by means passing between the roof sheets, said ridge caps retaining said ridge 130

covers in central alinement, said ridge covers having pivot bosses at their middles and said roof sheets having pivot bosses registering with the pivot bosses of said ridge 5 covers, and means for loosely securing the eaves ends of said roof sheets, whereby said roof sheets are retained on said substructure.

3. A car roof comprising roof sheets having upstanding flanges at their ridge ends provided with horizontal extensions adapted to lap over the ridge, pivot bosses at the middle points of said extensions, the bosses of overlapping roof sheets registering with 10 each other, ridge seam covers straddling the overlapping extensions of the ridge flanges of oppositely arranged roof sheets, said seam covers having pivot bosses fitting the pivot bosses of said roof sheets, and 15 means for retaining said ridge covers in central alinement on the car.

4. A car roof comprising spaced roof sheets having outwardly flanged up-standing ridge ends, pivots formed at the middle 25 points of said ends, ridge seam covers straddling the ridge flanges of oppositely arranged roof sheets, said seam covers having pivot bearings formed at their middle points registering with the pivots of said ridge 30 flanges, and means for retaining said ridge covers in central alinement on the car.

5. A car roof comprising roof sheets having up-standing flanges at their ridge ends, said ridge flanges having out-turned top 35 margins provided with pivots at their middle points, ridge seam covers straddling the ridge flanges of oppositely arranged roof sheets, said seam covers having side walls which diverge from the ridge flanges of the 40 roof sheets to provide wide spaces between their bottom edges, the top walls of said seam covers being provided at their middle points with pivot bearings for said ridge flanges, and means for retaining said ridge

covers on the car, said ridge covers having 45 out-turned flanges along the bases of their side walls which bear upon the roof sheets.

6. A car roof comprising loosely connected roof sheets having outwardly projecting flanges along the tops of up-standing flanges 50 along their ridge ends, ridge seam covers of inverted channel-shape covering said flanges, the side walls of said ridge seam covers being spaced from said flanges, and the top walls thereof having pivotal connection to 55 said outwardly projecting flanges at their middle points.

7. A flexible car roof comprising a series of pairs of oppositely disposed roof sheets extending from eaves to ridge and loosely 60 connected along their side margins, the ridge ends of said roof sheets being raised and bent outwardly and provided with pivots at their middle points, the middle points of the roof sheets of each pair being located 65 in juxtaposition, ridge seam covers over the ridge ends of said pairs of roof sheets, said ridge seam covers having socket portions midway of their length which are adapted to receive said pivots and to bear upon said 70 roof sheets near their pivot points, whereby said roof sheets can swing about their ridge ends, and means for securing the ends of the ridge seam covers.

8. A ridge cap for a car roof, said ridge 75 cap having an up-standing boss at its middle adapted to coöperate with a similar boss on a roof sheet.

9. A ridge cap for a car roof, said ridge cap having a flat top and side walls provided with flanges for stiffening it against vertical and sidewise bending, said flat top having a circular boss at its middle adapted to coöperate with a similar boss on a roof sheet. 80

Signed at New York, N. Y., this 29th day of September, 1915.

ALBERT C. MURPHY.
